CASING FOR A DIAL INDICATOR

Zygmunt Natkanski, 6609 W. Melrose St.,
Chicago, Ill. 60634

Filed Sept. 4, 1970, Ser. No. 24,838

Term of patent 14 years

Int. Cl. D10—05

U.S. Cl. D52—6

FIG. 1 is a front elevational view of the casing for dial indicator showing my new design; and

FIG. 2 is a right side elevational view thereof; the left side being a mirror image thereof; and

FIG. 3 is a rear elevational view thereof; and

FIG. 4 is a top plan view thereof; and

FIG. 5 is a bottom plan view thereof.

I claim:

The ornamental design for a casing for a dial indicator, substantially as shown and described.
